PONTOON FOR BOATS

George W. Gregory, 355 M St.,
Fresno, Calif. 93721

Filed Oct. 10, 1966, Ser. No. 4,217

Term of patent 14 years

(Cl. D71—1)

FIG. 1 is a top plan view of a pontoon for boats showing my new design.

FIG. 2 is a side elevation thereof, the opposite side of the pontoon being identical to the side shown.

FIG. 3 is a bottom plan view thereof.

FIG. 4 is a front elevation thereof.

FIG. 5 is a rear elevation thereof.

FIG. 6 is a perspective thereof taken from the front and beneath.

FIG. 7 is a perspective from the front and above showing my new pontoon disposed in supporting relation to a boat deck and superstructure.

The broken line showing of the boat deck and superstructure, and an additional pontoon is for illustrative purposes only.

I claim:

The ornamental design for a pontoon for boats, as shown and described.
